United States Patent Office.

MARCELLUS V. CUMMING, OF WINTHROP, MAINE.

Letters Patent No. 77,719, dated May 12, 1868.

IMPROVEMENT IN MOWING-MACHINES.

The Schedule referred to in these Letters Patent and making part of the same.

TO ALL PERSONS TO WHOM THESE PRESENTS MAY COME:

Be it known that I, MARCELLUS V. CUMMING, of Winthrop, in the county of Kennebec, and State of Maine, have invented a new and useful Automatic Mowing-Machine; and I do hereby declare the same to be fully described in the following specification, and represented in the accompanying drawings, of which—

Figure 1 denotes a top view, and

Figure 2 a side elevation of it.

Figure 3 is a transverse section of it, taken longitudinally through the rear axle of its main carriage, and exhibiting the two engine-cylinders, with the boiler and the appurtenances thereof, in advance of the plane of section.

Figure 4 is a vertical section of the boiler, its covering, a spark-arrester, and smoke-pipe.

Such other figures as may be necessary to complete the proper delineation of my invention will be herein-after referred to and described.

The main object of my invention is to effect the mowing of a field of grass or the reaping of a field of grain by what is termed a steam-carriage, and certain mechanism to be operated by the steam-engine or engines of such carriage. To this end I have invented an automatic mowing-machine, whose steam-engine not only serves to impel such machine along over a surface to be mowed, but at the same time puts in operation the mechanism for mowing the grass or grain to be cut.

In the drawings; A denotes a platform or carriage-body, provided with two axles B C, each of them having two wheels applied to its two ends. The forward axle, C, carrying the smaller pair of wheels, turns vertically on a bearing or pin, a, going through the hub b of a worm-gear, e, so applied to a spring, d, as to be capable of being revolved in a horizontal plane, the spring being attached to the front part of the carriage-body, and being arranged therewith, as shown in Figure 5. The said figure is a front end view of the body, the axle, and the worm-gear. The carriage-body thus rests on the springs, while the latter is supported on the worm-gear, which in turn is sustained by the pin going through its hub and the axle. By applying a worm or endless screw to the said gear, and affixing to the carriage-body a shaft and means for revolving such screw, a person, while on the carriage-body, may effect the turning of the axle so as to change the direction of motion of the carriage as circumstances may require. The axle, by being able to turn in a vertical plane, will enable either of its wheels to readily pass over an obstruction, without at the same time and in like degree throwing up the other wheel, and rocking the carriage.

To the carriage-platform or body A, an upright tubular steam-boiler or generator, D, is fixed, such boiler being surrounded on its top and sides by a cylindrical case or spark-arrester, E, from the lower part of which the smoke-discharge pipe F rises in manner as represented. The smoke, after passing from the fireplace through the tubes of the boiler, rushes into the arrester E, thence passes down around the external surface of the boiler, and deposits the sparks on the bottom of the arrester, the smoke escaping by the pipe F.

There is fixed to the boiler a bracket or projection, G, which supports in bearings e the trunnions of two oscillating steam-engine cylinders I I, whose pistons K K' are applied to two cranks f f', projecting from a driving-shaft, L, which extends across the frame A, and is supported in suitable bearings applied thereto. One of the cranks I arrange at a right angle with respect to the other.

Furthermore, there is hinged to the frame A the finger-bar g of a cutting-apparatus, M, such bar being provided with teeth. The serrated knife h of such machine slides freely on the lower bar, and has a projection, i, extending from its inner end into a serpentine cam-groove, k, made in the periphery of a drum, N, fixed on the driving-shaft L. When the said shaft is in revolution, and the projection i is in the said groove, a reciprocating rectilinear motion will be imparted to the cutter-bar of the mowing-machine. The finger-bar may be turned up into a vertical position, and there be locked by a spring-catch, l, projecting from the frame A. On such bar being turned down, a roller or wheel, m, will rest on the ground, in which position the machine will be in a state for mowing grass.

A toothed pinion, m' , fixed on the driving-shaft, engages with a gear, n , on the rear-wheel axle of the carriage A. The gear n should be so applied to the axle as to be capable of being moved thereon either into or out of engagement with the pinion m' . Thus, while the driving-shaft may be in revolution, the mowing-machinery will not only be put in operation, but the rear axle of the carriage will be revolved, so as to effect a simultaneous forward propulsion of the carriage and the mowing-mechanism.

In order to facilitate the movement of the machine up an-acclivity, I apply to the main carriage A an auxiliary carriage or frame, O, provided with an axle, P, and two wheels Q Q, and I connect the said axle with the rear axle of the platform A by means of an endless chain, R, going about the grooved peripheries of two wheels S S', fixed to the two axles. I connect the two carriage-bodies A O by a projection, o, carrying a joint-pin, p, to extend down into a hole made vertically through the middle of the rear bar of the frame A, the said projection o being extended from the auxiliary frame O. By such means I am enabled to employ the axle P, its wheels, the endless chain and its wheels, as auxiliary means for effecting the propulsion of the carriage A; for, by having the additional friction of the axle-wheels on the ground, when such wheels are propelled by the endless chain and its wheels, so much additional means of propulsion is gained. The mode of connecting the two frames A O together enables the frame O to readily follow the frame A, when the course of the latter may deviate from a straight line.

One of the wheels of the rear axle of the carriage-body A, I fix firmly to the axle, so as to revolve therewith. The other wheel I so apply to the axle as to be capable of freely revolving on it, and I combine with such axle and the last-named wheel, a clutch, q, by which the said wheel and axle may be so connected as to cause the axle while in revolution to revolve the wheel.

In the above-described automatic mowing-machine or organism, I claim as my invention the following:

1. I claim the combination of a cutting-apparatus, M, a wheeled carriage, and a steam-engine applied to both, so as to put them in operation under circumstances and substantially in manner and for the purposes as hereinbefore explained.

2. I also claim the combination of an auxiliary wheel-carriage, O, and mechanism as described, (viz, the chain R and wheels S S'), or its equivalent, for revolving its axle with the mowing-machine, its wheel-carriage, and a steam-engine applied to both, so as to put them in operation, substantially as and for the purposes set forth.

MARCELLUS V. CUMMING.
